FIG. 2.

FIG. 1.

INVENTOR.

VINCENT F. CARLUCCI

BY

Richards & Geier

ATTORNEY.

UNITED STATES PATENT OFFICE

135,860

DESIGN FOR AN OVERALL OR SIMILAR ARTICLE

Vincent F. Carlucci, New York, N. Y.

Application June 10, 1942, Serial No. 107,168

Term of patent 7 years

To all whom it may concern:

Be it known that I, Vincent F. Carlucci, a citizen of the United States, residing in the city of New York, county of Bronx, and State of New York, have invented a new, original, and ornamental Design for an Overall or Similar Article, of which the following is a specification, reference being had to the accompanying drawing forming a part thereof.

Fig. 1 is a front view of an overall showing my design;

Fig. 2 is a rear view of the overall shown in Fig. 1.

I claim:

The ornamental design for an overall or similar article, as shown.

VINCENT F. CARLUCCI.
